AUTOMATIC PERCOLATOR

Ivar Jepson and Robert O. Ernest, Oak Park, Ill., as
signors to Sunbeam Corporation, Chicago, Ill., a cor-
poration of Illinois

Application June 9, 1954, Serial No. 30,890

Term of patent 14 years

(Cl. D44—26)

To all whom it may concern:

Be it known that we, Ivar Jepson and Robert O. Ernest, both citizens of the United States and residents of Oak Park, State of Illinois, have invented a new, original, and ornamental Design for Automatic Percolator, of which the following is a specification, reference being had to the accompanying drawings, forming a part hereof.

Fig. 1 is a perspective view of an automatic percolator, showing our new design;

Fig. 2 is a top plan view thereof;

Fig. 3 is a side elevational view thereof;

Fig. 4 is a front elevational view thereof on a reduced scale; and

Fig. 5 is a rear elevational view thereof on a reduced scale.

We claim:

The ornamental design for an automatic percolator, substantially as shown.
